UNITED STATES PATENT OFFICE.

WILLIAM J. BRENNAN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

PRESS.

Application filed March 21, 1919. Serial No. 284,149.

To all whom it may concern:

Be it known that I, WILLIAM J. BRENNAN, a citizen of the United States, residing at Swampscott, in the county of Essex and State of Massachusetts, have invented certain Improvements in Presses, of which the following description, in connection with the accompanying drawings, is a specification, like reference characters on the drawings indicating like parts in the several figures.

This invention relates to presses in which the presser members are relatively movable into different operative relations to each other, and particularly to presses designed 15 to cut sheet material by the use of freely movable dies.

Presses of the type just referred to are advantageously constructed with presser members having different presser surface 20 areas and in the preferred construction a movable presser member having a presser surface area considerably less than a stock supporting bed is movable over said bed to bring it into operative relation to a die placed upon different portions of the stock 25 which is supported upon the bed. As these machines are commonly constructed, the movable presser member must be moved into operative position by force exerted directly 30 by the operative, with the result that a very considerable part of the labor incidental to cutting operations is expended in overcoming the inertia of the relatively heavy presser member in moving it to the desired 35 operative position over the die and in moving it away from the die after a cutting operation.

It is an object of the invention to provide improved power means for moving the 40 presser member into and out of operative position over the cutting bed.

In one aspect the invention comprises an organization in which the power means for moving the movable presser member is operatively connected to swing the said member over the work supporting bed by flexible means arranged to rotate the support on which the presser member is mounted. In a preferred form of the invention the described flexible means comprises a cable connected to the vertically reciprocable and rotatable supporting post of the presser member, said cable having a portion arranged

to run in opposite directions accordingly as it is desired to move the presser member to 55 or from any selected position.

Other features and objects of the invention will be apparent from the following detailed description and will be pointed out in the claims.

In the drawings,—

Fig. 1 is a view in side elevation of a clicking machine embodying my invention;

Fig. 2 is a view similar to Fig. 1 of the lower portion of the machine showing the 65 power means for moving the presser member, and

Fig. 3 is a detail view of a portion of the mechanism for moving the presser member as seen from the rear of the machine.

In the illustrated machine, the frame 4 supports a cutting bed 6 and a co-operating presser member 8 which is mounted for swinging movement into and out of positions over the cutting bed. Mounted in bearings 75 10 in the frame is a post 12 to which the presser member 8 is fixedly secured, swinging movement of the presser member being secured, through rotation of the post. Extending through the base of the machine is 80 a shaft 14 which is operatively connected to the post 12 to cause vertical reciprocations of the same, the connecting mechanism being shown in the patent to Arthur Bates No. 921,503, granted May 11, 1909. Power is 85 transmitted to the shaft 14 through a pulley 16 which is arranged to be clutched to the shaft by clutch mechanism, also shown in said patent, and constructed to be controlled through a rod 18, lever 20, pivoted at 21 and 90 having at its forward end the handle 22. The machine thus far described may be controlled to effect the cutting of work placed upon the cutting bed 6 by means of the handle 22. The operative seizes said handle 95 to cause swinging movement of the presser member 8 through force exerted by the operative to place the presser member over the selected position of the die on the cutting bed. As the presser member approaches the 100 desired position the presser member is given its pressure applying movement by depressing handle 22, which, through the connections described, throws in the clutch and thus effects a vertical reciprocation of the 105 post 12 which carries the presser member.

As thus far described, the machine is identical with that disclosed in the said patent to Bates.

The power means for moving the presser member into and out of position over the cutting bed is shown in the illustrative mechanism to comprise a shaft 24 which is mounted for endwise movement in bearings 26 attached to a bracket 28 secured on the frame 10 of the machine. Shaft 24 is driven by a gear wheel 30 splined on the middle portion of the shaft 24 and arranged constantly in mesh with a worm 32 on a stub shaft 34 mounted in a bearing on the bracket 28 and 15 driven by a belt 36 passing around a pulley 38 fixed to the outer end of the shaft 34, the other end of the belt passing around a belt pulley 40 secured to or integral with the driving pulley 16 on the main shaft of the 20 machine. If it proves necessary or desirable, a belt tightening pulley 42 may be provided mounted on an arm 44 fixed to a bearing for the shaft 34, said pulley 42 engaging one run of the belt 36 on the outer surface 25 thereof, as shown in Fig. 3 of the drawings. The bearings 26 for the shaft 24 also provide bearing surfaces for a pair of drums 46 and 47, mounted on the bearings, one adjacent each end of the endwise movable shaft 24. 30 Passing around these drums is an endless cable 48, the cable being engaged with each drum through a plurality of coils and secured to each drum by any desired means, as by a screw or clip, so that rotative movement of either drum will cause movement 35 of the cable and of the other drum and of parts operatively connected to the cable as hereinafter described. In order to pass the cable from one drum to the other, there are 40 provided two idle pulleys 50 located below and between the drums on stub shafts 52 mounted in bearings on the bracket 28. After leaving the drums, the cable 48 is carried upwardly over idle pulleys 54 of 45 which one is shown in Fig. 1, located on bracket 56 extending from the frame of the machine and passed several times around a drum 58 secured to or integral with the upper end of the post 12. Preferably the 50 cable is secured to the drum 58 by means of a clip 49 in order to prevent slipping or creeping of the cable on the drum. It is clear that movement of the cable 48 in one direction will cause rotative movement of the post 12 55 to carry the presser member over the cutting bed 6 and that movement of the cable 48 in the opposite direction will cause corresponding rotative movement of the post 12 to carry the presser member 8 away from 60 operative position. Movement of the drums 46 to effect movement of the cable in the desired direction is obtained by engaging the shaft 24 with the proper drum through clutch members 60, 62, mounted one at each 65 end of the shaft 24 in position to engage its

respective drum 46 or 47. From an inspection of Fig. 3, it will be seen that movement of the shaft 24 to the right in said figure will cause engagement of the clutch 60 with the drum 46 and that movement of the shaft 24 in the opposite direction will cause engagement of the clutch 62 with its corresponding drum 47, there being a neutral position of the shaft 24 in which neither clutch is engaged with its respective drum. Means 70 is provided for causing the endwise shifting of the shaft 24 which comprises preferably a circular grooved member 64 fixedly secured to one end of the shaft 24 and providing through the groove 66 a rotative engagement with a bifurcated lever member 68 which is fixedly carried at one end of a shaft 70 mounted for rocking movement in bearings 72 on another portion 74 of the bracket 28. Manually operable means is provided 75 for rocking the shaft 70, said means being preferably in the form of a lever 76 secured to the shaft 70 at the forward end thereof and extending upwardly to provide a handle located preferably at one front corner of the 80 cutting bed in a position readily accessible to the operator. Preferably means is also provided for holding the rockshaft 70 in a position intermediate its extreme points of rotation, thus providing also for the 85 positioning of the shaft 24 in what may be termed the neutral position with both of the clutch members 60 and 62 disengaged from their respective drums. In the construction 90 shown the means for thus positioning the shaft 70 comprises a member 78 attached to the plate 74 of the bracket 28 and having arms 80 which extend on either side of the shaft 70 and carry plungers 82 arranged to engage on opposite sides of an arm 84 adjustably carried by the shaft 70. In the construction disclosed, the arm is carried by a 95 collar 86 secured by a set screw 88 for adjustment for positioning the arm 84 properly in the assembling of the machine. 100 Preferably the plungers 82 are received in sockets in the arms 80 and are pressed outwardly from said sockets by springs 89. 105

In order that the operations of the machine may be controlled most advantageously, the lever 76 is so connected with the power means for operating the machine that after the presser member has been brought into proper relation to the bed, it may be actuated to perform a pressing operation upon 115 a die located on the bed by further manipulation of the same lever 76. In the present embodiment of the invention the lever 76 is operatively connected to a lever 90 on the frame of the machine by means of a cable 120 94 which preferably passes around an idle pulley 96 as shown in Fig. 1, of the drawings. One end of the lever 90 is secured to the cable 94 and the other end is attached by a link 98 to the rear end of the starting lever 125 130

20. Hence, movement of the lever 76 to the right in Fig. 1 will result in tripping the clutch on the main shaft in the same manner that depression of the handle 22 accomplishes this result. In order that the lever 76 may have the movement just described, it is movably secured to the end of the shaft 70 by means which, in the present construction, comprises an arm 100 secured to the end of the shaft 70 by a collar member 102 in cooperation with a set screw 104. To the lower end of the arm 100 there is pivoted at 106 a link 108 which passes upwardly through a slot 110 in an extension 112 of the 15 collar member 102. Adjustably mounted in a socket 114 at the upper end of the link 108 is the lever member 76. The lever 76 is held in its normal position of rest by a bolt 116 which passes through alined openings in the 20 link 108 and the arm 100, a spring 118 being mounted on the bolt and operative to hold the link 108 yieldingly against an abutment 120, the arrangement being such that the lever 76 may be moved to the right in Figs. 25 1 and 2 against action of the spring 118 to cause the tripping of the clutch on the main shaft as described.

It will be observed that the power mechanism just described for moving the presser member is mounted upon the bracket 28 which has members embracing the frame of the machine below the cutting bed and which is held fixedly in position on the frame by means of set screws or locking bolts 122. 30 Furthermore, the cables are guided on idle rollers or pulleys which are mounted on brackets readily attachable to the machine. Hence the entire mechanism provided for controlling the operations of the presser member may be readily attached to machines already built and in use. It will be observed also that the mechanism described is so located that power connections may easily be made with the main shaft on the machine 40 and that the arrangement lends itself to the provision of a manually controllable lever so positioned with respect to the cutting bed as to be readily accessible without reaching over the cutting bed or into the path of the 45 presser member. Moreover, there is provided by the mechanism disclosed a relatively simple and easily controllable means by which the operative is enabled to cause the desired movements of the presser member 50 into and out of operative position and also the pressure applying movements thereof.

Means are preferably provided for limiting the swinging movement of the post and of the presser member carried thereby, the 60 said means being so constructed as to absorb the momentum of the heavy presser member and thus prevent a jarring blow of the presser member against the upright portion of the frame 4 should the presser member be 65 inadvertently carried so far to either side of

the cutting bed. In the illustrative construction, each pulley or drum 46 and 47 carries a stop member 124 integral therewith or fixedly attached thereto and arranged to travel in a path which will bring it up against a 70 co-operating stop 126 fixed to the bracket 28. This latter stop carries two plungers 128 between which is located a relatively strong spring (not shown) the arrangement being such that stop 124 will strike against 75 either the upper or lower plunger 128, depending on the direction the pulley is turning, just as the presser member is reaching the limit of its rotative movement in either direction from the cutting bed. In other 80 words, the stops 124 and 126 co-operate to stop the movement of the presser member so that the said member cannot come forcibly into contact with the frame 4. Since the drums turn in opposite directions, the stop 85 124 on one drum will strike the upper plunger 128 at the same time that the stop 124 on the other drum strikes the lower plunger. Since the cable 48 is fastened to both drums 46 and 47 and to the drum 58 an effective 90 stop mechanism in connection with the cable is provided.

In operating the machine described, the operative stands in front of the cutting bed 6 and places the sheet material on the cutting bed and the die in selected position on the work, during which time the presser member 8 is conveniently located at one side of the cutting bed 6, affording room to manipulate the die and permit the access 95 of light to the work. When the die has been properly placed, the operative grasps the lever 76 and moves it to cause rocking of the shaft 70 and endwise movement of the shaft 24 to throw the proper 100 drum into operation by which the cable is caused to travel and thus swing the post and presser member in the direction to carry the presser member over the die. When the presser member is nearly over the 105 die, pressure on the lever in the direction to cause rocking of the member 70 is relaxed and the lever simultaneously pulled toward the operative, thus tripping the clutch on the main shaft and causing a pressure applying movement on the pressure member. Upon relaxing the pressure on the lever 76 which caused the rocking of the shaft 70, the spring-pressed plungers 82 return the 110 rock-shaft to its intermediate position and thus effect the return of the endwise shiftable shaft 24 to its neutral position, disconnecting the drum from the shaft, thus terminating the driving movement of the cable 48. There is no need of waiting until 115 the presser member comes to rest over the die, since the machine embodies a brake mechanism which becomes operative to stop rotative movement of the post, and therefore the pressure member just as the presser 120 125 130

member is about to strike the die, said brake being fully disclosed in the patent to H. H. Eaton, granted Oct. 3, 1911, No. 1,004,757. It is possible, therefore for the operative to 5 control the movements of the presser member entirely through lever 76 without any direct manipulation of the presser member. Inasmuch as inertia of the relatively heavy presser member in presses of this kind has 10 slowed up the operation of the machine and reduced the efficiency of the operative because of the labor imposed in moving the presser member, it is clear that the provision of power means for effecting all necessary 15 movements of the presser member should result in increased efficiency both from the machine and the operative.

Having described my invention, what I claim as new and desire to secure by Letters Patent of the United States is:

1. In a machine of the class described, a cutting bed, a presser member, a post carrying said presser member, and means comprising a cable operatively connected to the 25 post for moving the presser member into selected position over the cutting bed.

2. In a machine of the class described, a cutting bed, a presser member, a post for carrying the presser member, a drum on 30 the post, and means comprising a cable arranged to pass around said drum for rotating the post and thereby causing the presser member to move into and out of operative position over the cutting bed.

3. In a machine of the class described, a cutting bed, a presser member, a frame for rotatably supporting said presser member, power means, a readily attachable bracket for supporting said power means on said 40 frame, and means for operatively connecting said power means with the presser member for causing swinging movement of the presser member into and out of operative position over the cutting bed.

4. In a machine of the class described, a cutting bed, a presser member, a post for rotatably supporting the presser member, and power means comprising a cable for causing rotation of the post in either direction to 50 place the presser member in operative position over the cutting bed.

5. In a machine of the class described, a cutting bed, a presser member, a post for rotatably supporting the presser member over the cutting bed, power means for causing rotation of said post, and a cable for connecting said power means with said post.

6. In a machine of the class described, a cutting bed, a presser member, a post for rotatably supporting the presser member, a frame in which the post is journaled for rotation, a bracket mounted upon the lower portion of said frame and below said cutting bed, power means for causing rotation of 60 the post mounted upon said bracket, and

means extending upwardly at one side of the cutting bed in a position accessible to the operator for controlling said power means to effect swinging movement of the presser member at the will of the operator. 70

7. In a machine of the class described, a cutting bed, a presser member, a post for rotatably carrying said presser member, and power means for causing rotation of said post comprising a constantly rotating 75 shaft, drums arranged to be driven selectively by said shaft, and a cable passing around said drums and operatively connected to said post.

8. In a machine of the class described, a cutting bed, a presser member, a post rotatably carrying said presser member, power means for causing rotation of said post comprising a cable, and means under the control of the operator for causing said 85 cable to run in opposite directions to cause rotation of the post to swing the presser member into or out of operative position over the cutting bed.

9. In a machine of the class described, a cutting bed, a presser member, a post rotatably supporting the presser member, power means comprising a cable for causing rotation of the post in either direction, power means for causing pressure applying movement of the presser member, and means under the control of the operator for controlling the direction of run of the cable and for causing the actuation of the 95 presser member.

10. In a machine of the class described, a cutting bed, a presser member, a post for rotatably supporting the presser member, and power means for causing rotation of the post comprising a constantly rotating 105 shaft mounted for endwise movement, a cable operatively connected to said post and arranged to be selectively connected to said shaft upon endwise movement of the latter in the selected direction, and means for returning the said shaft to neutral position.

11. In a cutting machine, a cutting bed, a presser member, a post for rotatably supporting the presser member, power means for causing rotation of the post comprising a cable, power means for causing pressure applying movement of the presser member, a cable for causing actuation of the last-mentioned power means, and means under the control of the operator for controlling both said cables.

12. In a machine of the class described, a cutting bed, a presser member, a post rotatably carrying the presser member, means for causing rotation of the post, and means for limiting the rotation of the post comprising a cable operatively connected to the post.

13. In a machine of the class described,

a work supporting bed, a presser member movable toward and from the bed in pressure applying operations and also laterally over the bed into and out of selected operative positions with respect thereto, power means for causing pressure applying operations of the presser member, power means for moving the presser member laterally over the bed comprising a cable connected 10 to the presser member, and a drum upon

which said cable is wound, a stop mounted on the frame of the machine, and a second stop mounted on the drum and so arranged as to co-operate with the first mentioned stop to limit the movement of the presser member in one direction. 15

In testimony whereof I have signed my name to this specification.

WILLIAM J. BRENNAN.
